ASH TRAY

Glave Spencer Bunch, Jr., South Bend, Ind.

Application July 5, 1947, Serial No. 759,046

10 Claims. (Cl. 131—237)

1

This invention relates to improvements in ash trays.

The primary object of the invention is to produce an ash tray which will accommodate the disposal of cigar and cigarette butts in a clean, sanitary and practical manner in which the burning butt is extinguished and is then discharged to a concealed container so that the butt will not continue to smoke and will not be visible after the device has been operated.

A further object is to provide a device of this character which is adapted to extinguish a cigar or cigarette and then deposit the same in a concealed receptacle and which is so constructed that the presence of ashes or tobacco remnants upon exposed and visible surfaces of the device is substantially avoided.

A further object is to provide a device of this character which is simple in construction and operation, which can be manufactured inexpensively, and which can be assembled and disassembled easily and rapidly and in a manner to facilitate exposure of all working parts thereof for purposes of cleaning and washing the same.

A further object is to provide a device of this character which may be used for the purpose of extinguishing and discharging a cigar or cigarette butt without danger of burning the fingers of the user.

Other objects will be apparent from the following specification.

In the drawing:

Fig. 1 is a top plan view of the device.

Fig. 2 is a view of the device in side elevation.

Fig. 3 is a vertical sectional view of the device taken on line 3—3 of Fig. 1.

Fig. 4 is a fragmentary vertical sectional view similar to Fig. 3, illustrating the device in cigarette extinguishing position.

Fig. 5 is a fragmentary sectional view of the device taken on line 5—5 of Fig. 4.

Fig. 6 is a bottom perspective view of the movable member of the device as viewed when rotated 180 degrees with relation to Fig. 7. Fig. 7 is a top perspective view of the body of the device.

Referring to the drawings which illustrate the preferred embodiment of the invention, the numeral 10 designates the body of the device which is preferably cast or molded from metal, glass, plastic or other suitable material. The body 10 is preferably of the construction shown in Fig. 7, and has a generally bowl-like form defined by the concavo-convex wall 12. A skirt portion 14 is formed integrally with the bowl portion 12 and depends from the convex side thereof concentrically therewith, as best illustrated in Fig. 3. A hollow cylindrical projection 16 is formed integrally with the body 10 at the center thereof and projects upwardly

from the concave face thereof to a level preferably below the level of the outer edge of the wall 12 of the body 10. Within the cylindrical member 16 is concentrically arranged a cup-shaped part 18 having an annular flange 20 at its upper end and defining a socket 22 open at the center of the convex face of the wall 12 of the body 10.

The body has a plurality of equally spaced enlargements or vertical radially positioned ribs 24 formed integrally therewith, said enlargements 24 being preferably four in number, as best shown in Fig. 1. Each of these enlargements has a recess 26 formed in its upper surface, which recess inclines generally downwardly and inwardly from the edge of the body and terminates and communicates at its inner end with a substantially vertical bore or passage 28 extending through the enlargement 24 and open at the bottom surface of the bowl-like wall 12 of the body at a point 28 spaced inwardly of the registering part 15 of the depending skirt 14, which may be projected outwardly as best shown in Figs. 3 and 4. One or more projections 30 extend upwardly from the recessed portion 26 of each enlargement 24 and each has a curved upper face to adapt it to support a burning cigar or cigarette in the position illustrated in dotted lines at 32 in Fig. 3, with its burning end bearing against the wall 34 defining the inner limit of the recess 26 and an extension of the wall of passage 28 so that the ash end thereof is directly above the passage 28. The inner wall 34 may have a projection 36 so positioned that the inner end of the cigar or cigarette 32 underlies the same to be held thereby against overbalancing. If desired, the body, adjacent to one or more of the enlargements 24, may carry a radially outwardly and upwardly projecting arm 38 supporting a concavo-convex plate 39 at its outer end which is aligned with the projections 30 which support the cigarette, for the purpose of supporting the outer end of the cigarette.

The upper or inner surface of the bowl-shaped wall is preferably slightly ridged radially at spaced positions at 40 between the adjacent enlargements 24 for the purpose of guiding a cigar or cigarette butt deposited thereon in a radial direction upon endwise inward sliding thereof, so that said butt 43 may slide to a position as best illustrated in Fig. 3 with its ignited end innermost and the butt extending substantially radially of the body.

A movable member 42, preferably of the construction illustrated in Fig. 6, is mounted centrally in the ash tray body 10, being provided with a central cylindrical bore 44 open at its lower end to snugly and slidably receive the cylinder 16 therein. A handle member 46 projects above the

body member 42 and has secured thereto, as by a threaded connection therewith, a stem or plunger 48 which projects centrally downwardly through the body member 42 and terminates in an enlarged head 50 which is slidably received in the socket 22. A coil spring 52 bears at its lower end against the concavo-convex wall 12 of the body 10 and is confined at its upper end in a cup-shaped member 54 which is anchored to the stem or plunger 48, as by a pin 56. The cup-shaped member 54 has a sliding telescopic fit in the cylinder member 16. The opposite ends of the coil spring 52 are preferably fixedly anchored to the body wall 12 and to the cup-shaped member 54, respectively. The major portion of the bottom surface 58 of the movable member 42 is preferably of concavo-convex form substantially conforming to the curvature of the central part of the upper face of the bowl 12 of the body. The spring 52 normally urges the shiftable member 42 upwardly to an upper limit position determined by the engagement of the head 50 of the plunger 48 with the flange 20 of the body member. A plurality of vanes 60, preferably of a number equal to the number of enlargements 24, depend from the body member 42 and are of such a size and proportion that in the normal spring-pressed relation of the parts as illustrated in Fig. 3, such vanes 60 will have a slight clearance with the upper surface of the bowl 12 of the ash tray. The vanes 60 extend in a generally radial direction normally aligned with the center of the adjacent enlargements 24, and slots 62 are formed in the bowl 12 in register with said vanes 60 to accommodate and receive said vanes 60 when the body member 42 is depressed against the action of the spring 52 for the purpose of bringing the bottom surface 58 of the member 42 into adjacent crushing relation with the upper face of the bowl 12.

As shown in Fig. 3 when the body member 42 is depressed against the action of the spring 52, any cigar or cigarette butts 43 which are deposited in the device for disposal, in the position as shown in said figure, will be pressed between the bottom surface 58 of the member 42 and the upper face of the bowl 12. This crushes the burning embers of the butt for the purpose of extinguishing the same. Thereupon the body member 42 may be released and returned to its Fig. 3 position so that the vanes 60 clear the bowl 12. The handle 46 may then be manipulated to rotate the body member 42 in a direction which will increase the tension of the spring 52 and cause an adjacent vane 60 to engage the crushed butt 43 and propel the same in advance thereof to the next adjacent passage 62 in the bowl 12 for discharge thereof through said passage 62. The device may then be released, whereupon the body member 42 will be reversely rotated by the tensioned spring 52 for return to its starting position.

A cup-shaped member having a base 64 and a marginal flange 66 is removably connected with the bottom structure of the device, as by means of a screw thread 68. This structure serves in combination with the skirt 14 to define a closed chamber into which the crushed cigar or cigarette butts 43 may be discharged as above described and also into which the ashes from cigarettes 32 supported at 30 may be discharged through the passages 28.

It may be desirable to provide means for limiting the extent to which the body member

42 may be rotated, and for this purpose a pin 70 may be carried by the body member 42 to project radially therefrom intermediate its height. A vertical groove 72 may be formed in the inwardly radially projecting enlargement 24 adjacent to said pin, being of a length to permit insertion of the parts into their proper assembly relations and of a depth sufficient to accommodate lowering of the body member 42 to the full extent of its downward movement for cigarette crushing action, as illustrated in Fig. 4. This groove 72 has a horizontal groove 74 communicating therewith at a level to receive the projecting end of the pin 70 when the parts are in the position illustrated in Fig. 3. The groove 74 is preferably of a length to accommodate a quarter turn of the movable member 42 in the construction illustrated. Thus rotation of the body member 42 is limited to that rotation which is required to insure that the vanes 60, considered collectively, will sweep the entire inner or central portion of the upper face of the bowl 12, each vane 60 being shifted from register with one opening 62 to a position registering with the next adjacent opening 62 at which it discharges the crushed butts 43 propelled thereby. This action provides stops or limits for the rotative movement, assuring the operator that he has turned the member 42 sufficiently to clear the bowl 12 of any crushed cigarette butts before he releases the handle for spring return of the member 42 to its normal position. Likewise the pin and slot arrangement prevents the downward movement of the body member 42 in the event the vanes 60 do not register with the openings 62 in the bowl 12.

This ash tray provides a simple construction which can be manipulated easily for the purpose of disposing of a cigar or cigarette in a manner which will prevent objectionable continued combustion or smoking of the cigar or cigarette after it has been discharged into the lower compartment of the device. All of the surfaces of the device which are engaged by the ashes of a cigar or cigarette are substantially invisible and the device remains clean of ashes and tobacco particles at exposed surfaces. This condition is true, not only with respect to cigars and cigarettes which are positioned in the bowl for disposal into the bottom chamber of the device, but also holds true with respect to cigars and cigarettes which are deposited upon the supports 30 between smoking intervals, since any ashes which may be discharged by a cigarette 32 are discharged through the passage 28. The device may be easily disassembled for the purpose of removing ashes and cigarette butts from the receiving chamber at the bottom thereof by manipulating the screw-threaded connection 68 between the base 64 and the remainder of the body. Likewise, the device may be readily disassembled for access to all parts thereof by simply disconnecting the handle 46 from the stem 48 at its screw-threaded connection with said stem. This permits the movable member 42 to be removed from the body 12, assuming that the pin 70 registers with the vertical groove 72. When this is done, the spring 52 will position the stem 48 and the inverted cup-shaped member 54 in operative position, as shown in Fig. 3, by virtue of the pinned connection between the cup-shaped member 54 and the stem 48.

In the preferred embodiment of the invention the upper surface of the body member 42 is preferably provided with ribs 76 extending ra-

dially thereof and substantially aligned with the enlargements 24 of the body member 10 in the normal position of the parts. Downwardly and outwardly tapering faces 18 are provided in the top of the body member 42 at the parts thereof facing and registering with the ridged outer portion 40 of the body member 10. Thus, if any cigarette is deposited carelessly in the device in a position to engage the upper surface of the body member 42, the inclined surface 18 of said member 42 will permit the cigarette to move by gravity away from said body member and onto the bowl 12 down which it can slide to a position beneath the body member 42.

The device is intended for use with both cigars and cigarettes, and in any case in which either is referred to herein, it will be understood that such reference is illustrative only and not limiting.

While the construction of the device as described and illustrated herein is preferred, it will be understood that changes may be made within the scope of the appended claims without departing from the spirit of the invention.

I claim:

1. An ash tray comprising a body having a dished portion and a receptacle below said dished portion, said dished portion having an opening communicating with said receptacle, a shiftable member, means mounting said shiftable member on said dished portion for vertical movement, and spring means normally urging said shiftable member to an elevated position spaced above said dished portion, said shiftable member having a convex bottom surface substantially conforming to the shape of said dished portion and adapted to crush against said dished portion a cigarette stub positioned therebelow.

2. An ash tray of the construction defined in claim 1, wherein said dished portion and said shiftable member have cooperating telescoping parts guiding movement of said member relative to said dished portion.

3. An ash tray of the construction defined in claim 1, wherein said dished portion and shiftable member have interfitting and interengaging parts for guiding movement of said member and including a stop for limiting spring pressed movement of said member.

4. An ash tray comprising a body having a dished portion and a receptacle therebelow, said dished portion having an opening communicating with said receptacle, a central tubular portion and an inverted apertured cup-shaped projection within said tubular portion, a shiftable member having a convex bottom surface interrupted by a cup-shaped member having a slideable guiding fit in said tubular portion, a coil spring fitting in said tubular portion and cup-shaped member to urge said shiftable member to elevated position relative to said dished portion, and a headed member carried by said shiftable member and extending longitudinally of said cup-shaped member with its head slideable in said cup-shaped projection to form a stop limiting spring pressed upward movement of said shiftable member.

5. An ash tray comprising a body having a dished upper portion and a chambered lower portion, a shiftable member, means mounting said member on said dished portion for rotative and vertical movement, spring means normally urging said member to an elevated position spaced above said dished portion and to a predetermined rotative position, said upper body

portion having a plurality of discharge openings therein communicating with said chambered lower portion, and a projection depending from said member in register with one of said discharge openings, the bottom edge of said projection clearing said dished portion in the elevated normal position of said member.

5 6. An ash tray of the construction defined in claim 5, wherein said discharge openings are 10 equi-angularly related and equally spaced in said dished portion, and a depending projection normally registers with each opening.

15 7. An ash tray of the construction defined in claim 5, wherein said discharge openings are 20 equi-angularly related and equally spaced in said dished portion, and a depending projection normally registers with each opening, and means for limiting rotation of said shiftable member to an angular extent corresponding to the angular spacing of said projections.

25 8. An ash tray comprising a body having a dished upper portion and a chambered lower portion, said upper portion having an inwardly 30 radially projecting enlargement at its outer portion,

25 said enlargement having a recessed upper 35 face adapted to support and position a burning cigarette, said enlargement having a substantially vertical passage communicating with said chambered lower portion and with the inner end of the recessed upper face of said enlargement, a shiftable member mounted on said dished portion inwardly of said enlargement for vertical and rotative movement, said dished portion having a discharge passage communicating with said chambered lower portion and positioned below said member, and means for normally urging said member to a predetermined position spaced above the dished portion registering with said member.

40 9. An ash tray of the construction defined in claim 8, wherein said shiftable member has a projection depending therefrom and normally positioned in register with said last named discharge passage and with the bottom surface of 45 said projection clearing the adjacent surface of said dished portion.

45 10. An ash tray of the construction defined in claim 8, wherein said dished portion has a plurality of said last named discharge passages 50 equally spaced and with one thereof substantially radially aligned with said enlargement, and substantially radial projections depending from said shiftable member and normally registering with said last named discharge passages with the bottom edges of said depending projections normally clearing the dished portion of said body.
